ABSTRACT OF THE DISCLOSURE

N-halo amides react explosively with alkyl sulfoxides and active hydrogen compounds such as certain hydroxy compounds and amines. Delayed explosive decompositions occurring after a predetermined time can be produced by selection of components and variation of their proportions.

BACKGROUND OF THE INVENTION

The present invention relates to spontaneously explosive compositions and to a method for generating an explosion under predetermined conditions.

Combinations of certain materials are known to be hypergolic, that is, ignition or explosion occurs on contact of the components. Such combinations are useful in rocketry and they are also sometimes employed to trigger a mechanical action or a larger explosion. The action is substantially instantaneous. Delayed action initiators such as the familiar black powder fuse of fireworks or other explosives are also known. Mechanically timed initiating devices have also been used to produce delayed explosions. The present invention provides a means whereby predetermined timed explosions can be produced by a novel chemical process.

SUMMARY OF THE INVENTION

It has now been found that when a di lower alkyl sulfoxide or an active hydrogen compound such as any of certain alcohols and amines is intimately contacted with an N-halo amide or N-halo imide, the halogen being bromine or chlorine, the mixture remains substantially unchanged in appearance and temperature for a measurable time ranging from a second or two to several minutes, and in some cases, as long as several hours or even days, then it suddenly decomposes explosively with flame formation and generation of considerable gas and vapor. By choice of particular components and proportions of these, the interval between contact and explosion can be adjusted to a predetermined desired length.

DETAILED DESCRIPTION

The N-halo amides of the invention are defined herein by that term as including any carboxamide, sulfonamide, or corresponding carboximide or sulfonimide having at least one chlorine or bromine atom attached to the amide nitrogen atom. Representative compounds include N-chloroacetamide, N-bromosuccinimide, mono, di, and trichloroisocyanuric acid, 1,2-dichloro-5,5-dimethylhydantoin, 1-bromo-3-chloro-5,5-dimethylhydantoin, N-N-dichloro-p-toluenesulfonamide, p,p'-oxybis(N,N-dichlorobenzenesulfonamide), N-chloro-2-pyrrolidone, N-chloro-5-methyl-2-oxazolidinone, N-chloro-2-morpholinone, N-chlorocaprolactam, and the like. Mixtures of such compounds may be employed. Particularly preferred are N-chloro-2-oxazolidinone and its lower alkyl substituted derivatives.

Organic hydroxy compounds of the present invention include primary and secondary alkanols of 2-7 carbon atoms, benzyl alcohol, phenol, and lower alkyl substituted phenols. Representative of the class of alkanols are

ethyl alcohol, propyl alcohol, isopropyl alcohol, n-butyl alcohol, isoamyl alcohol, and heptyl alcohol. Alkanols such as methanol, tert-butyl alcohol, and cyclohexanol are not operative. The class of lower alkyl substituted phenols includes the cresols, isopropylphenol, tert-butylphenol, xylenol, and their isomers.

Amines useful in the present invention are alkyl primary amines of 3 to about 8 carbon atoms wherein the alkyl group is of primary or secondary configuration. Such amines include propylamine, isopropylamine, n-butylamine, 2-aminoctane, and the like.

Lower alkyl sulfoxides which are operable include dimethyl sulfoxide, diethyl sulfoxide, methyl ethyl sulfoxide, dibutyl sulfoxide, and the like, wherein the alkyl groups are of primary or secondary configuration. The term lower alkyl is used herein in its usual sense to mean alkyl groups of 1-4 carbon atoms.

Mixtures of alcohols, of amines, of sulfoxides, or combinations of these classes can be used effectively in the invention.

Proportions of reactants which are operative in this invention are 0.02-50 parts by weight of di lower alkyl sulfoxide or an active hydrogen compound per part of N-chloro compound. When proportions of reactants outside this range are employed, the large excess of the one reactant tends to muffle the reaction so that no explosion takes place even though a reaction may occur.

The N-chloro-2-oxazolidinones and N-chloro-2-morpholinone and their N-bromo analogs are new compounds which are the invention of one of us and these are described and claimed in copending application Ser. No. 679,254, filed concurrently herewith and now abandoned. They may be prepared by halogenating the parent compounds with a haloisocyanuric acid as set forth in that application or by reacting the heterocycle with chlorine in the presence of an alkali as described by Tafel et al. Berichte 33, 2224 (1900).

The utility of the present invention to generate sudden pressure, initiate a mechanical action, or detonate a conventional explosive is evident, particularly where it is desired to have a short delay between action and reaction. The occasion often arises where it is desirable to provide a known time between the triggering action, as by crushing a capsule of one component in the other component, and the explosion without having to depend on a burning fuse or action of a mechanical timer.

Examples 1-9

A series of tests were conducted wherein one gram of an N-haloamide was contacted with a small amount of isopropyl alcohol and the interval between this contact and explosion of the mixture was measured. During these tests, the mixtures characteristically showed little or no change in appearance or temperature for a definite time, then they suddenly and violently decomposed with an explosive evolution of gas and sometimes with a visible flame.

60	N-halo amide	Isopropyl alcohol, ml.	Time to explosion, seconds
Trichloro-isocyanuric acid	0.05 0.10 0.15		15 17 6
Dichloroisocyanuric acid	1.0		11
1,3-dichloro-5,5-dimethylhydantoin	1.0		41
1-bromo-3-chloro-5,5-dimethylhydantoin	1.0		34.5
p,p'-Oxybis-(N-bromo-N-chlorobenzene-sulfonamide)	1.0		13
p,p'-Oxybis-(N,N-Dichloro-benzenesulfonamide)	1.0		76
N,N-dichloro-p-toluene-sulfonamide	1.0		20
Potassium dichloro-isocyanurate	1.0		200
N-chloro-5-methyl-2-oxazolidinone	1.0		2-3
	0.1		3
N-bromo-5-methyl-2-oxazolidinone	1.0		48

Examples 11-24

A series of tests were run substantially as described above wherein 0.3 ml. (or other quantity as noted) of a hydroxy compound was added to 1 ml. of N-chloro-5-methyl-2-oxazolidinone and the time before explosion was noted.

Hydroxy compound:	Time, seconds
Ethyl alcohol	78
Propyl alcohol	39
Isopropyl alcohol	4
Butyl alcohol	67
Isobutyl alcohol	39
Sec-butyl alcohol	3
n-Amyl alcohol	34
Isoamyl alcohol	79
n-Hexyl alcohol (0.1 ml.)	32
n-Heptyl alcohol	127
Isoheptyl alcohol	343
3-methyl-1-hexanol	231
Benzyl alcohol	24
o-Cresol (0.1 ml.)	3

When methanol, allyl alcohol, cyclohexanol, tertiary alcohols such as tert-butyl alcohol or diacetone alcohol, and polyhydric alcohols such as sorbitol were used as the hydroxy compound in the above tests, no explosive reaction resulted and the only visible change in these mixtures was, in some cases, a slight cloudiness or discoloration on standing for several minutes or hours.

Results similar to that shown above with o-cresol are obtained when the o-cresol is replaced by a phenol such as p-tert-butylphenol or xylenol.

Examples 25-27

Tests were run as in the foregoing examples wherein one gram quantities of an N-halo amide was contacted with 0.2 ml. of isopropylamine. In each case, the maximum temperature measured in the exploding mixture was determined.

N-halo amide	Time, seconds	Maximum temp., ° C.
Trichloroisocyanuric acid		114
N-chloro-5-methyl-2-oxazolidinone	about 1	213
N-bromo-5-methyl-2-oxazolidinone		210

Results comparable to those of Examples 25-27 are obtained when the isopropylamine is replaced by other primary amines as previously defined as n-butylamine, propylamine, n-hexylamine, or 2-aminoctane. In the same

way, the N-halo amide can be any of other such compounds as shown in Examples 1-10 and as herein defined with similar results.

Example 28

By the procedure of the foregoing examples, 1.0 gram of N-chloro-5-methyl-2-oxazolidinone was intimately contacted with 0.1 ml. of dimethyl sulfoxide. The mixture exploded after a lapse of 1.5 seconds, the exploding mixture attaining a maximum temperature of 165° C.

Similar results are obtained when another di lower primary or secondary alkyl sulfoxide is employed in place of dimethyl sulfoxide or when the N-halo amide is another as previously defined.

We claim:

1. A process for generating an explosion which comprises intimately contacting at least one N-halo amide, where the halogen is chlorine or bromine, and 0.02-50 parts based on the weight of N-halo amide of a reactive component which is at least one of a di lower primary or secondary alkyl sulfoxide, a primary or secondary alkyl primary amine of 3-8 carbon atoms, or an organic hydroxy compound which is a primary or secondary alkanol of 2-7 carbon atoms, phenol, a lower alkyl phenol, or benzyl alcohol.

2. The process of claim 1 wherein the N-halo amide is an N-chloro-2-oxabolidinone and the reactive component is a primary or secondary alkanol of 2-7 carbon atoms.
